ADJUSTING AND HOLDING MEANS FOR
ROTARY DISK TOOLS AND THE LIKE

Alvin E. Spindt, Hammond, Ind.

Application May 16, 1945, Serial No. 594,093

1 Claim. (Cl. 144—238)

1

The invention relates to means for adjusting a rotary tool of the disk type upon a rotary shaft so as to present the working periphery of the tool at a desired angle to the work and it consists in the constructions, arrangements and combinations herein described and claimed.

More specifically, it is an object of the invention to provide a rotary tool holder and adjusting means wherein the tool may be set at desired angles with respect to a rotary shaft upon which it is mounted, such angular adjustment of the tool controlling the path of peripheral travel of the working edge of the tool, which may vary from a straight rotary movement to a direction generally parallel to the rotary shaft.

It is also an important object of the invention to provide a tool holder particularly well adapted for the mounting and secure retention of circular disk devices, such as saws, buffing wheels, grinding wheels, brushes and similar appliances, upon shafts not especially constructed for the mounting of such appliances.

Additional objects, advantages and features of invention will be apparent from the following description considered in conjunction with the accompanying drawings, wherein

Figure 1 is a vertical section through the appliance as applied to a circular saw.

Figure 2 is a cross section on the line 2—2 of Figure 1.

Figure 3 is a sectional view of one of the adjusting collars.

Figure 4 is an inside plan view of one of the holding collars.

Figure 5 is a section on the line 5—5 of Figure 4.

Figure 6 is an elevation, partly in section, of a modified form of the appliance.

Figure 7 is a sectional view of the modified form of Figure 6, illustrating one stage of assembling upon a shaft.

Figure 8 is an end view thereof.

Figure 9 is a cross section on the line 9—9 of Figure 7.

Attention is first invited to Figure 1 of the drawings wherein there is shown a shaft 10, which may be rotated by means of any suitable power source, not shown, upon which the tool holder and adjusting means 11 is mounted.

The appliance 11 consists of a pair of adjusting collars 12 and 13, as will be described, and holding collars 14 and 15, which are identical in construction.

The adjusting collars 12 and 13 are of semi-spherical shape, providing a flat planiform face

2

16 adapted to rest flatly against a flat face of a tool to be secured upon the shaft, the spherical surface of the collars being presented outwardly for complementary seating engagement of respective holding collars, as will be explained.

A bore 17 is formed axially through the collars of a diameter at the planiform face 16 to receive the shaft 10 therethrough, the walls of the bore at diametrically opposite sides, tapering upwardly and downwardly as indicated at 18, the tapered walls terminating inwardly of the spherical surface and outwardly relieved to define respective shoulders 19 arranged in opposed relation to one another. The remaining wall portions of the bore extend parallel with the shaft 10 and are of the same diameter as the bore portion 17. Thus an elongated slot 20 is formed opening upon the spherical surface of the adjusting collars.

20 A pair of set screws 21 are threadedly engaged in bores 22 of the collar 12, arranged in opposed relation, the direction of travel of the screws corresponding to the major axis of the elongated slot 20.

25 Reference is now made to Figures 4 and 5, for an understanding of the construction of the holding collars 15, wherein it will be seen that the collars are formed with a semi-spherical recess 23 of a size to provide a fit upon the spherical face of the adjusting collar and permit oscillatory movement in one direction of the adjusting collars. Within the recess 23 a pair of lugs 24 are formed positioned upon diametrically opposite sides of an axial opening 25 formed through 30 the collars. The lugs 24 project from the recess 23 a distance, and are of a width to be received within the elongated slots 20.

35 A threaded bore 26 is formed in the collar 15 and receives a set screw 27, the bore extending so as to lie in the same plane as the elongated slot 20.

40 To install the appliance upon the shaft 10, the holding collar 14 is positioned upon the shaft as shown, and the adjusting collar 12 then moved into position upon the shaft, the spherical face being presented to the recess 23 with the lugs 24 disposed in the elongated slot 20. The tool 28 is now positioned on the shaft by presenting the latter through an axial opening 28' thereof. In 45 the present instance, the tool represents a circular saw, one flat side thereof engaging the planiform face of the adjusting collar 12. The adjusting collar 13 may now be positioned on the shaft and moved inwardly to dispose the planiform face against the saw body and finally

the adjusting collar 12 is arranged upon the shaft, the lugs 24 disposed in the elongated slot 20 and the recess seating upon the spherical face of the collar 12.

The collars 12 and 13 are forced into frictional contact with the saw and with the holding collars 14 and 15 by screwing the set screws 21 inwardly so as to engage in the keyways 29 formed in the shaft. The points of the set screws 21 tend to slide down the keyways moving the holding collars inwardly along the shaft thus effectively tightening the entire assembly.

Angular adjustment of the saw with respect to the shaft 10 is obtained by adjustment of the set screws 21, and as shown in Figure 1, the lowermost set screw 21 has been withdrawn and the uppermost screw has been moved inwardly, such adjustment of the screws effecting a rotary movement of the adjusting collars 12 and 13 to the left until the lugs 24 engage respective shoulders 19 with consequent movement of the saw, the peripheral edge of which is spaced from a transverse axis of the shaft 10, and under rotation of the saw and the tool holder, it will be seen that the teeth of the saw will follow individual lines of travel as indicated by dot and dash lines in Figure 1, and would produce a kerf 30 in a piece of work parallel to the shaft 10. It will be apparent that by the adjustment of the saw in angular relation with respect to the shaft, the need for setting of the saw teeth is eliminated, as well as avoiding the need for special saws for cutting wide grooves or kerfs.

Obviously, various degrees of tilt of the tool can be obtained quickly and accurately by merely adjusting the set screws 21 as required, without readjustment of the holding collar.

In the modified forms of the device shown in Figures 6 to 9, the structure of the holding and adjusting means is the same as the first form just described, except that the holding collars are each provided with a pair of diametrically opposite disposed set screws 21' and the adjusting collars 12 and 13 are similarly provided with set screws 21'. Also, the shaft 10 is shown as having a threaded end for mounting of a nut 31.

In Figure 6, the tool 28" is adjusted upon the shaft at right angles thereto so as to rotate in a path concentric thereto, but obviously the tool may be angularly adjusted with respect to the shaft by adjustment of the screws 21'. The degree of adjustment can be determined by the use of a graduated scale 32, fixed to a support not shown.

The holding collars 14 and 15 of Figure 7 are illustrated as slightly withdrawn from the adjusting collars 12 and 13 to more clearly illustrate the

construction, and also since the tool 28" represents a brush, the body of which is quite thick, the axial opening 33 is shown as of tapered formation, thus defining a reduced bearing contact with the shaft and permits adjustment of the brush to the desired angle.

While I have shown and specifically described the invention, this is by way of illustration only, and I consider as my own all such modifications in construction as fairly fall within the scope of the appended claim.

I claim:

Means for holding and adjusting a rotary disk tool at an angle with respect to a rotary mounting shaft extended axially therethrough, said means comprising a pair of semi-spherical members each having a planiform flat face adapted to engage respective sides of the disk tool, each semi-spherical member having an interior passage including a bore at said flat face of a diameter to receive said shaft, opposite portions of said passage tapering in an outward direction, the remaining portions of said passage being the same as said bore, the tapered portions of said passage being relieved to form shoulders inwardly of the spherical surface and to form an elongated slot on said spherical surface, holding collars removably securable on the shaft, each collar having a semi-spherical recess complementary to the spherical surface of said semi-spherical members, said collars having lug members disposed within respective elongated slots for holding said semi-spherical members against rotation with respect to the shaft, and set screws threadedly engaged in one of said semi-spherical members extended transversely across the tapered portions of said passage to contact said shaft at diametrically opposite sides and adjustable to move said semi-spherical members and said disk tool at an angle to the shaft.

ALVIN E. SPINDT.
